MAX LEVINE, OF BROOKLYN, NEW YORK.

BINDING.

Application filed November 23, 1927. Serial No. 235,358.

This invention relates to bindings.

In the manufacture of articles having an outer covering of imitation leather, or as it is known in the trade "leatherette", it frequently becomes necessary to apply a binding. It has been customary to cut strips from the "leatherette" and sew these strips together to form long tapes which are sold wound on spools or in rolls. In use these 10 bindings are unsatisfactory as the sewed junction of the strips is unsightly and pulls apart particularly when bent over an edge or corner. In the manufacture of articles the sewed seam frequently catches and 15 breaks in the gauge.

One of the objects of this invention is to provide a seamless leatherette tape for binding purposes. Still another object is to provide a seamless leatherette tape for 20 binding in which the cotton or other cloth base is on the bias. Still another object is to prevent breakage in the gauge.

Referring to the drawings:

Figure 1 is a view of the bias seamless 25 cloth base.

Figure 2 is a view of the binding after the application of the imitation leather coatings to the bias seamless cloth.

Figure 3 is a view of the leatherette binding partially folded for application as a 30 binding.

Figure 4 is a cross sectional view of Figure 3, along the line 4,4, looking in the direction of the arrows.

Figure 5, shows the application of the binding to an article of manufacture.

In carrying out my invention, I propose to use as a base, cloth on the bias and to interweave the ends of the strips to form

long binding tapes. The strips are then 40 coated with the imitation leather covering. Of course relatively wide strips can be made and these strips can be cut to any desired smaller width.

The cloth base 1, is on the bias and is 45 joined at 2, by interweaving one strip to another. The base 1 is then coated with a covering of imitation leather 3 to form binding 4. Having no seam the binding 4 can be turned in so that when used the cloth base 50 1 will not fray and the junction 2 will not be noticeable by a bulge when applied as a binding with the edges turned in as shown in Figure 5 where it is used as a binder for a suitcase.

At present in articles made of imitation leather their whole appearance is affected by the fraying of the cloth base of the binding and the disclosure of the stitching of the joints in the binding and their consequent separation.

It will thus be seen that I have invented a binding that will be neater in appearance, stronger, foldable without bulging, and one that will not tear in the gauge and one that 60 will not detract from the article's appearance.

What I claim is:—

A binding comprising strips of fabric having the threads of the fabric on the bias, 70 said strips joined end to end by interweaving to form long continuous binding tapes and coatings covering one side of the fabric base.

Signed at New York, in the county of 75 New York and State of New York this 9th day of November, A. D. 1927.

MAX LEVINE.
